UNITED STATES PATENT OFFICE.

HARVEY L. YOUNG, OF AKRON, OHIO, ASSIGNEE TO THE B. F. GOODRICH COMPANY, OF NEW YORK, N. Y., A CORPORATION OF NEW YORK.

WINDER-BALANCING MECHANISM.

Application filed August 18, 1921. Serial No. 493,257.

To all whom it may concern:

Be it known that I, HARVEY L. YOUNG, a citizen of the United States, residing at Akron, in the county of Summit and State 5 of Ohio, have invented a certain new and useful Winder-Balancing Mechanism, of which the following is a specification.

This invention relates to machines for winding a wire, a cord or a strip onto or 10 into a structure such as a cabled wire ring or gromet, a rope, a cloth or paper wrapping for a tire, etc., and its object is to provide means, preferably automatic in its action, 15 for variably counterbalancing the weight of the reel of wire, cord or the like during the revolution of said reel about the work, in order to compensate for the diminishing weight of the coil of wire or other material on the reel as said material is used up in the 20 work. The result is longer life and greater speed for the machine and greater safety in its operation.

Of the accompanying drawings, Fig. 1 is 25 a front elevation, partly broken away and in section, of portions of a winding machine equipped with a preferred form of my invention.

Fig. 2 is a section on the line 2—2 of 30 Fig. 1.

Fig. 3 is a section on the line 3—3 of Fig. 2.

Fig. 4 is a sectional view on the line 4—4 of Fig. 3 showing the screw-rotating ratchet and pawls, in their operative relation, together with the pawl-lifting means and lifter-retaining latch.

Fig. 5 is a sectional view on the line 5—5 of Fig. 3, but showing these parts after the pawls have been tripped to render the 40 weight-feeding screw inoperative.

In the drawings, 10 is a part of the machine frame and 11 is a stationary, hollow, annular guide or trough adapted to receive the work, which in this instance is a wire 45 gromet for a tire bead. 12 is a stationary bearing in the form of the major segment of an annulus mounted upon the frame 10 and rotatably supporting the winder ring 13, which is interrupted by a slot at 14, for passing the finished work transversely out of the machine. This ring is rotated by suitable gearing (not shown) and on one side has bolted thereto a forked holder 15 which carries a reel 16 for a coil of wire 17, forming

the material of which the gromet is made, 55 the reel being loosely journaled on a spindle 18 and having a tension mechanism consisting of a brake including the adjusting screws 19. The wire passes from the reel around a guide roller at 20 and between two 60 pairs of grooved feed-rollers 21, 22 which force it through a spiral passage in a bending die 23, so that the wire may be spiralled onto a core strand of wire in the gromet so as to lie properly in place thereon without 65 tending to unwind.

Through suitable gearing on the back of the machine (not shown) power is transmitted to a bevel gear 24 on the end of a sleeve journaled within the winder-ring 13, 70 and said gear is driven ahead at a predetermined rate faster than the angular speed of the winder-ring. The gear 24 meshes with a mating bevel-gear 25, loosely mounted on a shaft carried by a multiple bearing-bracket 75 26 on the opposite side of the winder-ring from the reel 16.

Fixed to the back of the bevel-gear 25 is a spur-gear 27 meshing with another spur-gear 28 attached to a shaft 29, which at one end drives the wire-feeding rollers 21, 22 through suitable gearing 30. On the opposite end of the shaft 29 is eccentrically mounted a crank-pin 31 (Fig. 2), to which is pivoted a drag-pawl 32, whose hooked end 80 engages the teeth of a ratchet wheel 33 which is held from reverse rotation by a check-pawl 34, this ratchet wheel having a cam-stud 35 projecting outwardly therefrom and engaging an arm 36 formed on a pawl-carrier 37, which oscillates freely about the axis of a shaft 38, whose inner end is fixed in the bearing-bracket 26. A spring 39 draws the pawl-carrier in a direction opposite to the movement imparted by the stud 35.

On a stud 40, mounted on the pawl-carrier 37, is pivoted a set of three feed-pawls 41, whose nose portions 42 engage the teeth of a ratchet wheel 43, secured to the inner end of a hollow screw 44, which latter is mounted 90 to turn upon the fixed shaft 38 and has a squared portion 45 at its outer end for receiving a crank tool to turn the screw by hand when desired. The pawls 41 are backed by springs 41^a, and the front or driving faces and under or lifting faces of the pawl noses 42 are relatively stepped so that the possible lost motion in a forward feed-

ing movement is less than the pitch-spacing or distance between any two adjacent teeth on the ratchet-wheel 43.

The screw 44 works in a nut 46, carried by a yoke 47 which constitutes an adjustable weight for counterbalancing the weight of the parts, including the reel 16 on the opposite side of the winder-ring, this yoke having a pair of parallel guide-rods 48 which slide in bearings 49 formed on brackets attached to the winder-ring 13. Inasmuch as the yoke 47 in the form of my invention here shown cannot be moved sufficiently close to the axis of revolution to keep the revolving masses fully in balance, I provide the inner ends of the rods 48 with a pair of auxiliary weights 50 which move from and past a line through said axis on the same side as the reel and thereby secure the proper balancing effect.

For the purpose of automatically throwing the screw feed out of operation at the limit of inward travel of the yoke 47, I provide a lifter-shaft 51, shown in detail in Figs. 3, 4 and 5, this shaft being flattened at two points in its length to form a cam portion 52 underlying the projections 53 on the pawls 41, and an offset abutment 54, whose path of movement during the reciprocation of the pawls will bring it into contact with a stud 55 carried by the yoke 47, as the latter reaches the inner end of its movement, this stud being adjustable to time the exact moment of occurrence of the tripping action by the turning of a pin 56 on which the stud is mounted. The inner end flange of the shaft 51 is backed by a spring 51^a which yields and prevents jamming of the parts in case the stud 55 should become wedged endwise against the abutment 54 at their first contact, the spring then restoring the shaft during the subsequent back-stroke of the pawl-carrier 37 so that a tripping engagement will occur on the next forward stroke. The shaft 51 carries an arm 57 adapted to snap past a spring-projected retaining-stud 58 when said shaft is turned back by the co-action of the members 54, 55.

59 (Fig. 1) is a bridge member pivoted at the inner end of the slot 14 in the winder-ring and adapted to be thrown out by centrifugal force to close said slot and prevent the wire from catching therein if the work should accidentally jump out of its guide 11.

55 In the operation of this mechanism the reel 16, containing a full coil of wire 17, is placed in the bracket 15, and the leading end of the wire is passed between the rollers 21, 22 and through the die 23 into the work-guide 11, while the winder-ring 13 is held from rotation. By manually reversing the screw 44 with a hand tool applied to its squared portion 45, the yoke 47 may be brought to the starting position shown in Fig. 1 and the power may then be thrown on

to revolve the parts carried by the winder-ring and cause the wire to be wound about the core strand in the guide 11. As the wire is fed into the gromet in said guide, the weight of the coil 17 diminishes. In each rotation of the shaft 29 caused by the action of the gears 24, 25, 27 and 28, the cam stud 35 produces an oscillation of the pawl-carrier 37 which causes the pawls 41 to reciprocate over a range of several teeth on the ratchet wheel 43, and thereby turn the screw 44 in a direction to draw the nut 46 and yoke 47 inwardly toward the axis of revolution, and this inward movement of the yoke continues until the coil of wire is exhausted or until enough has been fed out to form one gromet, the extent of each successive movement of the yoke being so calculated with reference to the weight of the corresponding used portion of the wire that the center of gravity of the rotating mass is kept approximately at the axis of rotation and the machine can therefore be run at a comparatively high speed without danger and without producing excessive wear in the bearing of the winding ring. Should the yoke reach the limit of its inward travel before being stopped by the operator, the continued turning of the screw 44 will be automatically stopped by the bringing of the trip-stud 55 into the path of reciprocation of the abutment 54 on the lifter-shaft 51, thus causing the cam 52 on said shaft to lift the noses of pawls 41 out of connection with the feed-ratchet 43. The winder may then continue to revolve without causing damage to the screw-feed mechanism.

The above-described embodiment may be variously modified without departing from my invention.

I claim:

1. In a winding mechanism, the combination of a winder-ring, a reel mounted thereon, work-driving means carried by said winder-ring and adapted to be driven during the revolution thereof for withdrawing material from said reel, a weight mounted on said winder-ring and adapted to be moved thereon to compensate loss of material from said reel, and means timed with said work-driving means for so moving said weight.

2. In a winding mechanism, the combination of a winder-ring, a reel mounted thereon, a weight mounted on said winder-ring and adapted to be moved thereon to compensate a variation in the amount of material on said reel, means on said winder-ring for so moving said weight, a roller carried by said winder-ring and adapted to run upon the work adjacent said reel, and a positive driving connection between said roller and said weight-moving means.

3. In a winding mechanism, the combination of a winder having a reel mounted to re-

volve about the work, a counterbalancing weight on the opposite side of the axis of revolution from said reel, an auxiliary weight adjustable toward and from said axis 5 on the same side as the reel, and means operable during the rotation of the winder for adjusting said auxiliary weight away from said axis.

4. In a winding mechanism, the combination of a winder having a reel holder adapted to revolve about the work for withdrawing material from said reel, a shiftable weight for controlling the position of the center of gravity, and means actuated by 10 said material-withdrawing means for automatically moving said weight relatively to the axis of revolution as the winder rotates.

5. In a winding mechanism, the combination of a winder having means on one side 20 of its axis of revolution for feeding material into the work, a counter-balancing member on the opposite side of said axis, a nut and a screw for moving said member from and toward said axis, and means actuated by 25 said material-feeding means for rotating one of said nut and screw.

6. In a machine for making wire gromets, the combination of a gromet support, a winder-ring encircling the same and provided with a wire reel on one side of its axis 30 of revolution, means on said winder-ring for withdrawing wire from said reel, a counterbalancing member on the opposite side of said axis, and means actuated by 35 said wire-withdrawing means for automatically feeding said member inwardly towards said axis.

7. In a winding mechanism, the combination of a rotary winder having a source 40 of material supply on one side of its axis of revolution, a shiftable weight controlling the position of the center of gravity, means for automatically moving said weight relatively to said axis as the material is used 45 up in the work, and means timed with the movement of said weight for automatically disabling the weight-moving means at the limit of movement of said weight.

8. In a winding mechanism, the combination of a rotary winder having a reel on one side of its axis of revolution and a counterbalancing member on the opposite side, feeding means adapted to be actuated during the rotation of said winder for imparting a step-by-step movement to said member toward the axis of revolution, and means 55 timed with the movement of said counterbalancing member for throwing said feeding means out of action.

60 9. In a winding mechanism, the combination of a winder having a reel holder on one side of its axis of revolution, a shiftable weight controlling the position of the center of gravity, a nut connected with said

weight, a screw carried by the winder and 65 engaging said nut, and means adapted to be actuated during the rotation of said winder for turning said screw, the last said means including a pawl and ratchet mechanism carried on said winder. 70

10. In a winding mechanism, the combination of a rotary winder having a reel holder on one side of its axis of revolution, a shiftable weight controlling the position of the center of gravity, and means for imparting a movement to said weight relatively to said axis, said means including a ratchet wheel controlling the position of the weight, a pawl adapted to be reciprocated during the rotation of the winder, a pawl-lifter reciprocating with the pawl, and a tripping device movable with the weight and brought at the limit of its travel into the path of a part on said lifter for automatically retracting the pawl. 80 85

11. In a winding mechanism, the combination of a rotary winder having a reel on one side of its axis of revolution, a counterbalancing yoke on the opposite side of said axis, a nut on said yoke, a screw on the 90 winder engaging said nut, and means on the winder for guiding the ends of said yoke in a direction transverse to said axis.

12. In a winding mechanism, the combination of a rotary winder having a reel on 95 one side of its axis of revolution, a counterbalancing member on the opposite side of said axis, movable in a direction transverse to said axis, and an auxiliary weight attached to said member and movable on the 100 same side of the axis as said reel.

13. In a winding mechanism, the combination of a rotary winder having a reel on one side of its axis of revolution and a counterbalancing yoke upon the opposite 105 side, guides on said winder for the ends of said yoke, a pair of auxiliary weights on the ends of the yoke movable on the same side of the axis as said reel, and means operable during the rotation of said winder for moving the yoke inwardly toward said axis. 110

14. In a winding mechanism, the combination of a winder having a reel holder on one side of its axis of revolution, a shiftable weight controlling the position of the center 115 of gravity, a nut connected with said weight, a screw carried by the winder and engaging said nut, and means adapted to be actuated during the rotation of said winder for turning said screw, the last said means including a plurality of pawl and ratchet mechanisms carried by said winder and so related as to multiply their speed reduction ratios. 120

In witness whereof I have hereunto set 125 my hand this 13 day of August, 1921.

HARVEY L. YOUNG.

Certificate of Correction.

It is hereby certified that in Letters Patent No. 1,455,185, granted May 15, 1923, upon the application of Harvey L. Young, of Akron, Ohio, for an improvement in "Winder-Balancing Mechanism," an error appears in the printed specification requiring correction as follows: Page 3, line 11, claim 4, after the word "work" insert a comma and the word, *means*; and that the said Letters Patent should be read with this correction therein that the same may conform to the record of the case in the Patent Office.

Signed and sealed this 11th day of September, A. D., 1923.

[SEAL.]

KARL FENNING,
Acting Commissioner of Patents.
